(57) **CLAIM**

The ornamental design for a plumbing fitting, as shown and described.

DESCRIPTION

In a preferred embodiment, the nature of this product is a plumbing fitting in the form of a faucet handle.

FIG. 1 is a right, top, front perspective view of a plumbing fitting according to my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a left, top, front perspective view of a plumbing fitting according to another embodiment of my new design, the front elevational, top plan, rear elevational, bottom plan, right side elevational and left side elevational views thereof being mirror images of FIGS. 2-7, respectively.

The broken line representations in the figures are for the purpose of illustration only, and form no part of the claimed design.
